UNITED STATES PATENT OFFICE.

THOMAS A. BRADY, OF PHILADELPHIA, PENNSYLVANIA, ASSIGNOR, BY MESNE ASSIGNMENTS, TO HIMSELF AND WILLIAM BRADY, OF SAME PLACE.

TAKE-UP AND DROP-BOX GOVERNING MECHANISM FOR LOOMS.

SPECIFICATION forming part of Letters Patent No. 559,768, dated May 5, 1896.

Application filed November 23, 1892. Serial No. 452,927. (No model.)

To all whom it may concern:

Be it known that I, THOMAS A. BRADY, a citizen of the United States, and a resident of Philadelphia, Pennsylvania, have invented 5 certain Improvements in Take-Up and Drop-Box Governing Mechanism for Looms, of which the following is a specification.

The object of my invention is to provide a loom with mechanism whereby the movement 10 of the take-up and of the drop-box chain will be arrested on the stoppage of the loom caused by the action of the weft-fork, said parts remaining out of action during the time that the loom is being operated by hand, so that 15 when the loom is again thrown into action said take-up and drop-box mechanism will be in precisely the same position as when the loom was knocked off. This object I attain in the manner hereinafter set forth, reference 20 being had to the accompanying drawings, in which—

Figure 1 is a perspective view showing sufficient of a loom to illustrate the application 25 of my invention thereto, the parts to which the invention particularly relates being shown in full lines and the remaining parts in dotted lines. Figs. 2 and 3 are perspective views, on a larger scale, illustrating parts of the loom to which the invention relates; and Fig. 30 4 is a view illustrating a modification of one of the details of the invention.

In Fig. 1, A represents the usual weft-fork connected to a rock-shaft a, which has an arm a', connected by a cord a² to a pivoted finger b, carried by a bell-crank lever b', the latter being hung to the side frame of the loom and acted upon by a cam on the main shaft, as usual, so as to impart a reciprocating movement to the finger b. When the weft-thread 35 40 is properly shot into the open shed of warp-threads, said weft-thread will on the forward beat of the lathe strike the weft-fork and push the same forward, so as to swing the rock-shaft a and lift the finger b to a point 45 above a lug d on a slide d', which I call the "weft-fork tripper-slide" and which is guided on the frame of the loom. Hence the forward motion of the finger has no effect upon said weft-fork tripper-slide; but in the absence 50 of a weft-thread in position to strike the weft-

fork A the latter is not moved forward and the finger b is permitted to hang down, so as to strike the lug d and move the slide d' forward, a depending finger d² at the outer end of the slide in such case acting upon one arm 55 of a trip-lever f, the other arm of which acts upon the shuttle stop-lever g, hung to the under side of the breast-beam, the outer end of said lever thereupon pressing upon the spring shifter-lever g' and releasing the same from 60 the notch in the retainer-plate g², so as to permit it to swing outward and shift the clutch on the main shaft, so as to throw the loom out of gear.

The swinging lathe has a projecting stud i, 65 which enters a slot in a lever i', hung to the frame of the loom and carrying a pawl i², which acts upon a ratchet-wheel m, constituting the primary wheel of the take-up train, the shaft of said wheel having a spur-pinion 70 m', meshing with a spur-wheel m² on the shaft of the take-up roll, any backward movement of the ratchet-wheel m being prevented by means of a retaining-pawl i³, hung to the pivot-stud of the lever i'. 75

The drop-box chain n is actuated by a reciprocating bar n', which receives movement from a cam n² on the main shaft, said cam acting upon a pivoted toe or finger n³, hung to the bar n'. All of these parts are common 80 to looms as now constructed and form no part of my invention, except as they may be combined with the novel devices which I employ and which I will now proceed to describe.

On the inner side of the weft-fork tripper-slide d' is a lug or projection 1, and with this lug is adapted to engage a spring catch or retainer 2, hung to the side of the loom, so that when the slide d' has been pushed forward by the finger b the retainer will engage with said 85 lug 1, as shown in Fig. 3, and will hold the slide so far as regards any accidental backward movement of the same, but will permit it to be moved back when sufficient force is applied to it. 90

Upon the rock-shaft 3, which carries the trip-lever f, I mount an arm 4, connected by a suitable link 5 to an arm 6 on a lever 7, suitably hung at some fixed point and adapted to act upon the retaining-pawl i³ of the ratchet- 95 100

wheel m , so that when the slide d' is pushed forward said retaining-pawl will be lifted from engagement with the teeth of the ratchet-wheel and there will be no forward movement of said wheel or of the take-up roll until the pawl has been again permitted to drop into engagement with the teeth of the wheel, an operation which is not effected until the clutch-operating lever g' has been pulled into the notch of the retainer-plate g^2 in order to again start the loom, this operation having the effect of pushing back the slide d' under the action of the lever f .

The rock-shaft 3 has at the other side of the loom an arm 8 , connected by a cord 9 to the pivoted toe n^3 on the reciprocating bar n' , which operates the pattern-chain, and the same movement of the rock-shaft 3 which actuates the lever 7 and lifts the pawl i^3 causes such movement of the arm 8 as to lift the toe n^3 out of the path of the cam n^2 . Hence as soon as the loom is knocked off there will be no operation either of the take-up mechanism or of the drop-box pattern-chain, the throwing of the loom again into gear, however, restoring both take-up and drop-box chain to operative position, the loom thus starting again with the take-up and drop-boxes precisely at the points which they occupied when the loom was stopped.

Although in carrying out my invention I prefer to adopt the construction which I have shown and described, various modifications of the mechanism within the scope of my invention will readily suggest themselves to those skilled in the art. For instance, instead

of using a spring catch or retainer for holding the weft-fork tripper-slide in its position of advancement a frictional retainer might be used for the purpose—such, for instance, as an elastic or semielastic washer w , interposed between the top of the slide and the nut which confines the same to the frame of the loom, as shown in Fig. 4—and the lever 7 might be so located as to lift the operating-pawl i^3 out of action instead of the retaining-pawl i^2 , and other minor details may be modified in various ways.

Having thus described my invention, I claim and desire to secure by Letters Patent—

The combination of the weft-fork tripper-slide of the loom, the drop-box pattern-chain, the bar for operating the same, a pivoted toe or finger on said bar, a cam acting on said toe or finger to reciprocate the bar, take-up mechanism having as elements a ratchet-wheel and pawl, and a rock-shaft having three arms one acted upon by the weft-fork tripper-slide, one connected to the toe on the pattern-chain bar so as to lift the same out of engagement with its operating-cam, and the other connected to mechanism for lifting the pawl out of engagement with the take-up ratchet, substantially as specified.

If testimony whereof I have signed my name to this specification in the presence of two subscribing witnesses.

THOMAS A. BRADY.
